[57] CLAIM

The ornamental design for a control panel for a control valve for use with a tourniquet system, as shown and described.

DESCRIPTION

FIG. 1 is a perspective view of a control panel for a control valve for use with a tourniquet system showing my new design;

FIG. 2 is a front view thereof;

FIG. 3 is a top view thereof.

FIG. 4 is a rear view thereof.
The left side (not shown) is the same as the right side shown, and the bottom side (not shown) is the same as the top side shown.
